UNITED STATES PATENT OFFICE

2,190,752

BRAILLE SLATE

Robert Brown, Johnstown, Pa.

Application April 7, 1939, Serial No. 266,665

7 Claims.

(Cl. 35—38)

The invention relates to an improved Braille slate for use by the blind for holding a sheet of paper while embossed dots and groups of embossed dots are formed therein to represent different characters.

Heretofore Braille slates have been constructed with hinged upper and lower plates, the lower plate containing one or more rows of groups of indentations and the upper plate provided with apertures corresponding to the groups of indentations and having in their edges recesses for enabling a stylus to be accurately positioned with respect to the indentations for embossing a sheet of paper. Interruptions in embossing or writing frequently occur and heretofore, when it has been desired by the writer or operator to read the embossings previously made, it has been necessary to remove the paper from the Braille slate in order to feel the embossed dots produced on the lower face of the paper by the stylus. The removal of the paper from the Braille slate for this purpose necessitates replacing the paper within the slate to continue the writing or embossing, and this is not only inconvenient and involves loss of time but frequently results in inaccurately replacing the paper within the slate, which may result in imperfect writing or embossing.

It is an object of the present invention to provide a Braille slate having said upper and lower plates and provided with means associated with the same for holding a sheet of paper in proper embossing position over the lower plate and capable of permitting the upper plate to be raised and lowered for placing the paper in position and for advancing the paper in the slate for bringing into embossing position another section of the paper after a section thereof has been embossed, said means being also adapted to permit the lower plate to be swung open or away from the paper for exposing the lower embossed face of the paper for reading without releasing the paper or necessitating its removal from the slate and its replacement therein.

A further object of the invention is to provide a Braille slate of this character equipped with a border or marginal frame hinged to the upper and lower plates by the hinge connection thereof and surrounding the groups of indentations of the lower plate and the apertures of the upper plate at the sides and free ends of the plates and forming an abutment for the free ends of the plates and provided at its upper face with means cooperating with the upper plate for accurately holding a sheet of paper in proper posi-

tion for embossing and also for reading the characters embossed thereon when the lower plate is open or swung away from the border or marginal frame.

Another object of the invention is to provide means for positively securing the lower plate in its closed position with relation to the marginal or border frame and thereby render it unnecessary to hold the lower plate manually in its closed position while writing or embossing and at other times.

With the above and other objects in view, the invention consists in the construction and novel combination and arrangement of parts herein-after fully described, illustrated in the accompanying drawing and pointed out in the claims hereto appended, it being understood that various changes in the form, proportions and minor details of construction, within the scope of the claims, may be resorted to without departing from the spirit or sacrificing any of the advantages of the invention.

In the drawing:

Figure 1 is a perspective view of a Braille slate constructed in accordance with this invention and having the upper and lower plates open or swung away from the marginal or border frame to illustrate the construction thereof and paper holding means carried by the same.

Figure 2 is a plan view of the Braille slate, the paper holding means of the marginal or border frame being illustrated in dotted lines.

Figure 3 is a longitudinal sectional view taken on the line 3—3 of Figure 2.

Figure 4 is a transverse sectional view taken on the line 4—4 of Figure 2.

Figure 5 is a reverse plan view of a portion of a Braille slate illustrating a modification of the invention in which a catch is provided for holding the lower plate positively in its closed position.

Figure 6 is a longitudinal sectional view of the Braille slate shown in Figure 5 and broken away for convenience of illustration.

Referring particularly to Figures 1 to 4, inclusive, of the drawing, the Braille slate comprises in its construction a lower plate 1, an upper plate 2 and a marginal or border frame 3. The upper and lower plates, which are constructed of sheet metal or other suitable material, are substantially oblong and are provided at one end of the slate with aligned eyes 4 and 5, through which passes a pintle 6 which hinges the upper and lower plates together.

The marginal frame 3, which is also construct-

ed of sheet metal or other suitable material, is substantially U-shaped, being composed of straight parallel sides 7 and a transverse connecting portion 8 located between the free ends 5 of the upper and lower plates 2 and 1 and forming an abutment for the same to enable the operator in grasping the Braille slate to conveniently hold both the upper and lower plates in their closed positions in contact with the marginal frame while using the Braille slate.

10 The sides 7 of the border frame are provided at the hinge connection between the upper and lower plates with eyes 9 which receive the terminal portions of the pintle, the latter being 15 extended beyond the side edges of the upper and lower plates for enabling the hinge connection of the upper and lower plates to serve also as the means for hinging the border frame to the upper and lower plates so that either one of said 20 plates may be opened and closed with relation to the border frame. This will enable the Braille slate to be opened for introducing the paper into the slate and for removing it therefrom and will also enable the lower plate to be opened or swung 25 away from the border frame for the purpose of exposing the embossed surface of the paper to permit reading of the embossed dots without removing the paper from the slate.

30 The sides 7 of the border frame are provided adjacent the hinged end thereof with inwardly extending lugs 10 located within recesses 1a of the bottom plate 1 and forming supports for short pins or projections 11 which are adapted to pierce a sheet 12 of paper or other suitable material to be embossed. The pins or projections 35 11 which are located at opposite sides of the border frame adjacent the hinged end thereof are disposed in transverse alignment and are adapted to securely hold the sheet of paper at one 40 edge thereof when the upper plate is closed. The paper is similarly held at the opposite side edge thereof by a pair of pins or projections 13 which are mounted on the transverse portion 8 of the border frame, as clearly illustrated in Figure 45 1 of the drawing.

50 In introducing the paper in the Braille slate, the sheet is placed upon the border frame while the lower plate is in its closed position and the upper plate is open. The upper plate is then closed and firmly clamps the paper in engagement with the pins or projections. The upper plate is provided at the pins or projections with perforations 14 which receive the said pins or 55 projections when the upper plate is closed. This will enable the upper plate to clamp the sheet of paper firmly without straining or otherwise injuring the pins or projections which are of sufficiently small diameter to enable them to pierce readily a sheet of paper.

60 The lower plate is preferably provided with four rows of the groups of indentations and the upper plate is provided with four rows of the apertures corresponding to the groups of perforations, but the Braille slate may be made of 65 any desired dimensions and any number of the rows of indentations and apertures may be provided.

70 The upper plate is preferably provided with a central transverse rib 15 and with spaced bosses 16 adapted to form guides for enabling the operator to readily locate the different areas of the slate. The free end of the upper plate is provided with a slightly raised segmental portion 17 forming a finger or thumb grip to enable the 75 upper plate to be readily opened by the thumb

or finger. Also the lower plate is provided with a segmental cut-out portion 18 to facilitate opening the lower plate, which, in practice, may be readily opened by releasing the same and slightly jarring the slate if the lower plate should not 5 readily swing open by gravity.

In Figures 5 and 6 of the drawing is illustrated a modification of the invention in which a sliding catch 19 is mounted on the transverse portion 20 of the border frame 21 for positively holding the 10 lower plate 22 in its closed position. The catch 19, which may be constructed of any suitable material, projects at its outer end slightly beyond the transverse portion of the border frame to provide a finger piece or grip 23 and the inner 15 end 24 extends slightly over the outer face of the bottom plate for engaging the latter to hold the same in closed position. The catch is provided with a longitudinal slots 25, through which passes a headed fastening device 26 consisting 20 preferably of a rivet or pin mounted on the transverse portion 20 of the border frame 21. The lower plate 22, the border frame 21 and an upper plate 27 are hinged together at 28 in the same manner as the corresponding parts of the 25 form of the invention illustrated in Figures 1 to 4, inclusive. The upper and lower plates and the border frame shown in Figures 5 and 6 are of the same construction as those heretofore described, and further description and illustration 30 thereof are deemed unnecessary, except perhaps to note that the transverse portion 20 of the border frame 21 extends beyond the free ends of the upper and lower plates 27 and 22, respectively.

The catch 23 positively holds the lower plate 35 in its closed position while the Braille slate is in use and at other times, and the lower plate may be readily released for opening by sliding the catch 19 outwardly. Any other suitable form of catch may, however, be employed for this purpose as may be readily understood.

What is claimed is:

1. A Braille slate comprising upper and lower plates hinged together at one end of the slate, and a hinged border frame composed of spaced sides 45 and a connecting portion extending between the free ends of the upper and lower plates and forming an abutment for the same and provided with paper engaging means, the spaced sides of the border frame being provided adjacent the hinge 50 connection of the plates with paper engaging means extending beneath the upper plate and cooperating with the same to enable a sheet of paper to be clamped by the upper plate on the border frame. 55

2. A Braille slate comprising upper and lower plates hinged together at one end of the slate, and a hinged border frame composed of spaced sides and a connecting portion extending between the free ends of the plates and provided adjacent the hinge connection of the plates with inwardly extending lugs, said border frame being provided at said lugs and at said connecting portion with paper engaging means. 60

3. A Braille slate comprising upper and lower plates hinged together at one end of the slate, and a hinged border frame composed of spaced sides and a connecting portion extending between the free ends of the plates and provided adjacent the hinge connection of the plates with inwardly 70 extending lugs extending beneath the upper plate and located within recesses of the lower plate when the plate is closed, said border frame being provided at the lugs and at the connecting portion with paper engaging projections and the 75

upper plate having apertures receiving the projections.

4. A Braille slate including hinged upper and lower plates, a hinged border frame having spaced sides and a connecting portion extending beneath the free end of the upper plate and across the free end of the lower plate, and a catch mounted on the connecting portion of the border frame and arranged to engage the free end of the lower plate for positively holding the same in closed position.

5. A Braille slate comprising upper and lower plates hinged together at one end of the slate, and means cooperating with the upper plate for clamping a sheet of paper in the slate between the upper plate and the said means and independently of any clamping action of the lower plate so as to obviate removal of the paper from the slate and enable the operator to read the embossing on the under face of the paper when the lower plate is moved to opened position.

6. A Braille slate comprising upper and lower plates hinged together at one end of the slate, and a border frame hinged to the slate by the

hinge connection of the upper and lower plates and arranged to support a sheet of paper in position for the same to be clamped between the upper plate and said frame, the lower plate being movable to open position to expose embossings on the lower face of the paper to thereby obviate removal of the paper from the slate for reading purposes.

7. A Braille slate comprising upper and lower plates hinged together at one end of the slate, and a border frame hinged to the slate by the hinge connection of said plates and composed of spaced sides and a connecting portion arranged between the free ends of the upper and lower plates and forming an abutment for the same, said border frame forming a support for a sheet of paper and to enable clamping of the paper between it and the upper plate, the lower plate being movable to open position to expose the embossings on the lower face of the paper and thereby obviating removal of the paper from the slate for reading purposes.

ROBERT BROWN.
